UNITED STATES PATENT OFFICE

2,493,855

ROPE GLIDER

David H. Bucks, Milwaukee, Wis.

Application June 20, 1947, Serial No. 756,075

2 Claims. (Cl. 116—173)

1

This invention relates to rope gliders, and more particularly, has reference to a device of this character for use in attaching flags to flagpole halyards.

An important object of the invention is to provide a device of the character described that can be used on flagpoles mounted either vertically, horizontally, or at some intermediate angle, the device being further fully efficient for use on poles that are either tapered, or constant in diameter.

Another important object of the invention is to provide such a device that does not have to be attached in any way to the pole itself, the device being connected entirely to the flag and to the halyards.

A further important object of the invention is to provide a rope glider of novel formation which will eliminate twisting of the halyards during the raising or lowering of the flag, and which will effectively prevent any slack from appearing between the corners of the flag whereby the flag is attached.

Still another object is to provide a glider which is capable of being constructed with a minimum of expense, and with very few parts simply arranged, but which nevertheless is unusually durable and efficient in use.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawing

Figure 1 is a side elevational view, showing a flagpole and halyard of conventional construction, there being a flag attached to the halyard by means of gliders constructed in accordance with the invention.

Figure 2 is a plan view of the glider, a portion of a flag attached thereto being also shown.

Figure 3 is a side elevational view of the glider.

Figure 4 is a view taken substantially on line 4—4 of Figure 2.

Referring to the drawing in detail, a flagpole of conventional formation is designated by the reference character P, with the reference characters A and B designating respective halyard sections also of conventional construction, which are connected to the pole by means of the usual

pulley arrangement, whereby when one of the halyard sections moves upwardly, the other moves downwardly.

My invention embodies a body portion 5, which is preferably formed from a block of metal or the like, and is of relatively thickened formation, as particularly shown in Figures 3 and 4. In the embodiment illustrated, this is shown as being of substantially rectangular formation, but as will be apparent from the complete description of the device, it may be of other configuration without departure from the spirit of the invention.

In one side wall of the body portion 5 is formed a recess 6, and a projection 7 is extended from one end thereof, whereby the recess is partially closed. A spring member 8 is secured to the body portion 5 at one end, as by a screw 9 or other suitable fastening means, the other end of the spring member normally lying in engagement with the adjacent end of the projection 7, the spring member thus normally serving to close the remaining portion of the recess 6.

Thus, it is seen that a ring or grommet R, in one corner of the flag F, can be entered into the recess 6, by means of manual pressure applied to direct the spring member 8 inwardly, said member springing back to its normal position upon the pressure being relieved.

At 11 is shown a substantially enlarged opening, which is preferably flared as at 12, at either end thereof. This opening is of considerably greater diameter than the diameter of halyard section A, and it is seen that halyard section A will freely slide therethrough, without the possibility of binding. The opening 11 is, as clearly shown in Figures 2 and 4, disposed adjacent one end of the body portion 5, and is substantially centrally disposed relative to the sides of the body portion.

Adjacent the other end of the body portion 5 is formed a second large opening 13, through which halyard section B is positioned. Preferably, the body portion 5 is so proportioned as to its dimensions that these openings 11 and 13 will be disposed relatively close to each other, it being found that this is particularly desirable in the case of tapered flagpoles, in order that the halyard sections A and B will remain close to each other at all times, further removing the possibility of binding or wear thereon.

A threaded opening 14 is formed in the end of the body portion 5, communicating between the outer surface thereof and the opening 13, as best shown in Figure 4. Threadable in this open-

ing is a thumb screw 15, which may have a head knurled as at 16 for the purpose of facilitating the operation thereof. A comparatively large and thickened block 17 is carried by the inner end of the thumb screw 15, and is preferably 5 swivelly mounted thereon, as shown at 18.

By operation of the thumb screw 15, the block 17 forces the halyard section B against one wall of the opening 13, and upon threading the thumb screw 15 inwardly, a sufficient amount, the result is obtained of tightly retaining halyard section B in fixed position relative to the body portion 5. It may be noted in this connection that the wall of the opening 13 can be recessed as at 19, to receive the halyard section, preventing its slipping off to the side.

In operation of a device constructed in accordance with the invention, the attaching rings R of the flag are each attached to one of identically constructed devices made as shown and 20 described.

It will be understood in this connection that the halyard sections A and B will already have been passed through the respective openings 11 and 13.

When the flag F has been so connected, the thumb screws 15 are used to tighten each of the two gliders to the halyard section B, the distance between the gliders being of course first adjusted for the purpose of removing any slack between the corners of the flag. Then, to raise the flag, halyard section A is pulled downwardly, sliding through the openings 14 in the respective gliders.

The position of the gliders, as shown in Figure 1, is in a plane substantially perpendicular to the halyard sections A and B, this being due to the fact that the body 5 and presser foot 17 are thick (see Fig. 4), so as to engage a sufficient portion of the length of the section B as will produce the result of perpendicular extension of the body 5 from the section B.

What is claimed is:

1. A glider for flagpole halyard sections comprising a solid body having a pair of close spaced openings extending from top to bottom thereof through each of which a halyard section passes,

each opening being of substantially greater diameter than the diameter of the section extending therethrough, a thumb screw threaded through a side wall of the body into one of the openings, said screw and the wall of said opening adapted for engagement between them of a portion of one section sufficiently long as to cause the body and the engaged section to be retained in perpendicular relation against relative movement, and means on the marginal portion of the body for catching a corner of a flag thereto.

2. A glider for flagpole halyard sections comprising a thick body having a pair of close spaced openings extending from top to bottom thereof through each of which a halyard section passes, each opening being of substantially greater diameter than the diameter of the section extending therethrough, a thumb screw threaded through a side wall of the body into one of the openings, a presser foot of a thickness corresponding approximately to the thickness of the body and mounted upon the inner end of the thumb screw to press the section extending 15 through said opening tightly against the wall of the opening, to hold the engaged section and the body against relative movement with the body extending perpendicularly from said section, and means on the marginal portion of the body for 20 attaching a corner of a flag thereto.
